A. RUBIN.
LOOSE LEAF BINDER.
APPLICATION FILED APR. 16, 1917.

1,271,227.

Patented July 2, 1918.

UNITED STATES PATENT OFFICE.

ADOLPH RUBIN, OF ST. LOUIS, MISSOURI, ASSIGNOR TO SIEBER PRODUCTS MFG. CO., OF ST. LOUIS, MISSOURI, A CORPORATION OF MISSOURI.

LOOSE-LEAF BINDER.

1,271,227.

Specification of Letters Patent.

Patented July 2, 1918.

Application filed April 16, 1917. Serial No. 162,324.

To all whom it may concern:

Be it known that I, ADOLPH RUBIN, a citizen of the United States, residing at St. Louis, Missouri, have invented a certain new and useful Improvement in Loose-Leaf Binders, of which the following is a full, clear, and exact description, such as will enable others skilled in the art to which it appertains to make and use the same.

10 This invention relates to loose leaf binders of the type which comprise tapes, bands or cords arranged in slots in the leaves and connected to a winding shaft that is adapted to be turned in one direction to draw 15 the tapes taut and cause the leaves to be clamped securely together by two coöperating leaf-clamping members, one of which carries the winding shaft.

One object of my present invention is to 20 provide a novel locking mechanism for the winding shaft.

Another object is to provide a novel means for securing the tapes to one of the leaf-clamping members of the binder.

25 And still another object is to provide a novel means for connecting the covers of the binder to the leaf-clamping members.

Figure 1 of the drawings is an end view of a loose leaf binder constructed in accordance with my invention.

30 Fig. 2 is a vertical sectional view of the binder, taken on the line 2—2 of Fig. 1.

Fig. 3 is a horizontal sectional view, taken on the line 3—3 of Fig. 2; and

35 Fig. 4 is a sectional view, taken on the line 4—4 of Fig. 3, illustrating the construction of the clips that are used for connecting the ends of the tapes to one of the leaf-clamping members.

40 Referring to the drawings which illustrate the preferred form of my invention, A and A' designate two leaf-clamping members between which the rear edge portions of the leaves B are arranged, C designates

45 tapes, bands or cords of flexible material that pass through slots in said leaves and in said leaf-clamping members and D designates a winding shaft to which one end of the tapes C are connected, the opposite ends 50 of said tapes being connected to a flange 1 on the leaf-clamping member A' and said winding shaft being provided at one end with a finger piece D' by which it can be turned.

The winding shaft D is rotatably mounted in a bearing or bearings 1^a on the leaf-clamping member A and a locking means of novel construction is provided for preventing the winding shaft from turning in a direction to slacken the tapes after said 60 tapes have been tightened. Said means consists of a ratchet wheel 2 securely connected to the winding shaft and arranged at the lower end of same and a torsion spring 3 provided with a part that serves 65 as a pawl which coöperates with the ratchet wheel 2 to prevent the winding shaft from turning in one direction. The torsion spring 3 extends the entire length of the leaf-clamping member A and is mounted in 70 bearings 4 on said member. At one end of the spring 3 is a laterally-projecting arm 5 provided with an extension 6 and at the opposite end of said spring is a laterally-projecting arm 5^a provided with an extension 6^a. The extension 6 of the arm at the lower end of the torsion spring coöperates 75 with the ratchet wheel 2, and the extension 6^a of the arm at the upper end of said torsion spring projects into the upper end of 80 a tubular-shaped part 7 on the leaf-clamping member A. A winding shaft locking mechanism of the construction above described can be manufactured at a low cost; it will not wear out quickly on account of 85 the fact that the spring of same is a torsion spring that will retain its resiliency even after long continuous use, and still another desirable feature of such a locking mechanism is that the spring of same is of such 90 a character that it effectively prevents the shaft from being turned in one direction and still does not offer considerable resistance to the shaft when it is being turned in a direction to tighten the tapes, thereby enabling the winding shaft to be manipulated 95 easily.

The covers E of the binder are connected to the leaf-clamping members by flexible hinges, each of which is formed from a piece 100 of fabric, leather or other pliable material 8 connected at one edge to its coöperating cover and having its opposite edge portion arranged in the tubular-shaped portion 7 on the leaf-clamping member with which it co- 105 operates. The edge portion of the flexible hinge member 8 that is connected to the leaf-clamping member is preferably provided

with a bead that is snugly surrounded by the tubular-shaped portion 7 on the leaf-clamping member. One convenient and inexpensive way of connecting the hinge members 8 to the leaf-clamping members is to form a bead on the edge portion of each of said hinge members by means of a piece of wire 9 around which the edge portion of the hinge member is wrapped, then slip said bead laterally underneath a portion on the leaf-clamping member that has been turned over or curved slightly, and thereafter, close said curved portion or bend it into substantially tubular form, so as to form the portion 7, previously referred to. A flexible hinge of the construction above described can be manufactured at a low cost, and there is little liability of its being accidentally detached from the leaf-clamping member to which it is secured, owing to the fact that it is provided at one edge with a bead that is completely surrounded by a portion on the leaf-clamping member that is bent over same.

25 The tapes C are connected to the flange 1 on the leaf-clamping member A' by means of clips 10, as shown in Fig. 3, each of which consists of a substantially U-shaped member, formed from sheet metal, that is slipped over the end portion of the tape after the tape has been lapped over or wrapped around the flange 1, as shown in Fig. 3. Said clips 10 are connected to the flange 1, preferably by pressing portions 11 of each clip into holes 12 in the flange, as shown in Fig. 4, thereby producing an efficient and inexpensive means for securing the tapes to the leaf-clamping member A' of the binder.

40 Having thus described my invention, what I claim, and desire to secure by Letters Patent, is:

1. A loose leaf binder of the type described provided with a winding shaft, a leaf-clamping member on which said shaft is rotatably mounted, a toothed portion on said shaft, and a torsion spring on said leaf-clamping member that co-operates with said

toothed portion to prevent the winding shaft from being turned in one direction. 50

2. A loose leaf binder of the type described provided with a winding shaft, a leaf-clamping member on which said winding shaft is rotatably mounted, a ratchet wheel on said shaft, a torsion spring arranged in bearings on said leaf-clamping member, means for connecting one end of said spring to said leaf-clamping member, and a portion at the opposite end of said spring that co-operates with said ratchet wheel to prevent the winding shaft from turning in one direction. 60

3. A loose leaf binder of the type described provided with a winding shaft, a leaf-clamping member on which said shaft is rotatably mounted, a ratchet wheel on said shaft, a torsion spring arranged in bearings on said leaf-clamping member and extending the entire length of same, a laterally-projecting arm at one end of said spring provided with an extension that co-operates with said ratchet wheel, and a laterally-projecting arm at the opposite end of said spring provided with an extension that fits in an opening in said leaf-clamping member. 75

4. A loose leaf binder, comprising leaf-clamping members, tapes or bands that pass through slots in the leaves, a flange on one of said leaf-clamping members, and clips secured to said flange and arranged so that they embrace portions of said tapes that are wrapped around said flange. 80

5. A loose leaf binder, comprising leaf-clamping members, one of which is provided with a flange, tapes or bands that pass through slots in the leaves and through slots in said leaf-clamping members, one end of each of said tapes being lapped over said flange, and substantially U-shaped clips arranged over the portions of the tapes that lap over said flange and secured to said flange by portions on said clips that are pressed into holes in said flange. 85 90

ADOLPH RUBIN.
